TAKEO OIWA, OF TOYOTAMA GUN, TOKYO FU, JAPAN.

APPARATUS FOR MANUFACTURING CHLORATES BY AN ELECTROLYTIC PROCESS.

1,297,395.

Specification of Letters Patent. Patented Mar. 18, 1919.

Application filed July 23, 1918, Serial No. 246,308.

To all whom it may concern:

Be it known that I, TAKEO OIWA, subject of Japan, resident of No. 1637 Nakano, Nakano Machi, Toyotama Gun, Tokyo Fu, Japan, have invented certain new and useful Improvements in An Apparatus for Manufacturing Chlorates by an Electrolytic Process, of which the following is a specification.

10 This invention relates to an apparatus for manufacturing chlorates by an electrolytic process, and consists of a series of cells each of which has an anode consisting of a number of platinum wires arranged on the inner 15 surface of the cell and a cylindrical cathode, either solid or hollow, fitted at the center of the cell, the electrolyte entering from the bottom thereof, filling the small space left between the anode and the cathode, and 20 overflowing from the upper part of the cell to the lower part of the next cell. The object of this invention is to increase electrolytic efficiency by shortening the distance between the electrodes, making the electrolyte to flow uniformly through the space between the electrodes, and adjusting the temperature of electrolyte and the density of electric current according to the concentration of the electrolyte.

25 Referring to the drawing annexed,

Figure 1 is a vertical section of a cell constructed according to my invention, part of the cell being broken off.

Fig. 2 is a plan of the same, being a section on the line A—B.

Fig. 3 is a plan view of the cathode supporter; and

Fig. 4 shows the arrangement of cells and crystallizing vessels.

30 The same reference numbers refer to the same or corresponding parts throughout all the figures.

To a bottom (1) of glass, porcelain or the like, having a shape of inverted cone and 35 provided with a flange (6), is inserted a cathode supporter (2) which has also a shape of inverted cone so as to fit the bottom (1). On its cone surface, radiating from the apex, this cathode supporter (2) 40 has a number of grooves, and on its plane or upper surface, at the center, it is provided with a projection (4). To this bottom (1) is connected a tube or cylinder (7) of glass, porcelain or the like, having 45 flanges (8) at its both ends with packing of any suitable material. Upon the cathode

supporter and supported by the projection thereof, is placed concentric with the cell body a cylindrical cathode of graphite or any other suitable material, either solid or hollow; and on the inner surface of the cell body are arranged a large number of platinum wires (10), which form an anode. The lower ends of these platinum wires are firmly fixed at the junction of the cell body 50 and its bottom; and the other ends are bent outward along the upper flange of the cell body and are connected with one another by a ring (11), which forms the anode terminal. The cathode is firmly held at its upper 55 part from sides by a ring (13) having a number of projections (31), and is provided with a terminal (12) of copper rod or the like at its center. Upon the cathode is placed a head piece (15) of porcelain or 60 the like, which is provided with pipes (16) for the gas to escape and a hole (34) to receive the terminal (12) of the cathode. This head piece (15) is connected with a glass cylinder (14) by means of an india rubber 65 ring (17), the said glass cylinder (14) being connected by means of a flange provided at its lower end with the cell body (7). Through this head piece (15) is inserted a thermometer (18). At the upper part of 70 the cell, as an outlet of the electrolyte, there is fixed an inverted T shaped pipe (21), the upright arm of which communicates with a burette (19), with a pinch cock (20) provided between them, so that a measured 75 quantity of an oxidizing agent can be poured as desired while electrolysis is going on. The third arm communicates with the lower end of the next cell through a tube (22). (See Fig. 4). At the lower extremity of the cell is fitted a cross-pipe, one arm (24) of which is connected through a pipe (23) with the outlet pipe of the next preceding cell. The other two arms (25) 80 (26) serve respectively to get rid of precipitates and to draw off the electrolyte for testing. The cell is on its outside provided with any suitable appliance for heating it or to prevent radiation of heat therefrom.

85 As is shown in Fig. 4, the cells of my invention are arranged in a series in the following manner:

The bottom of the first cell (A¹) is connected with a reservoir (32) of electrolyte, and the outlet pipe thereof is connected with 90 the bottom of (A²), the outlet pipe of which leads in turn to the bottom of (A³), and

so on, until the last cell is reached. The cathode terminals of these cells are connected by a conductor (27), and the anode terminals, by a conductor (28), in such a way that the two conductors (27) and (28) are parallel to each other. The last cell leads by means of a pipe (29), which can be easily connected or disconnected, to the first of a series of crystallizers (B) which are connected with one another and provided with a valve (30) between any adjacent two, the last of the crystallizers leading into a drain pipe (33).

My invention works in the following manner:—

A solution of potassium chlorid or any other chlorid is introduced from the reservoir into the first cell from its bottom. The fluid fills the cell, receiving electrolytic action while passing upward constantly and uniformly the small space between the cathode and the anode, and the resulting gas escaping from the pipes at the head part of the cell. The fluid thus partially electrolyzed overflows through the outlet pipe into the next cell, then into the next, and so on. The perfectly electrolyzed fluid constantly overflows from the last cell of the series into a series of crystallizers; and when the crystallizers of the first series are filled, the outlet pipe of the last cell is connected with a second series of crystallizers, then to a third series, and so on. Then commencing with a series of crystallizers in which crystallization has been perfected, the mother liquor is drained away through the drain pipe and the crystallized chlorate is scraped off into the receiver provided below.

This invention has the following advantages over the process hitherto used:—

1. The electrolytical efficiency is greater, because according to this invention the electrodes are kept in short and uniform distance, and electrolyte circulate between them thoroughly and at uniform speed.

2. As the electrolyte and the gas evolved therefrom never come into contact with the terminals of the electrodes, there is no fear of their junctions to be corroded.

3. As the cell is perfectly closed with insulating substance excepting the openings left for the gas and vapor to escape, the gas can be collected and turned into advantage. Further as the cell is covered with a suitable substance, there is no fear of vapor and the like condensing on the outside, and consequently there is no possibility of electricity to leak.

4. The cathode can easily be changed.

5. The outside of the cell will never be soiled by the electrolyte, gas, or the like, and consequently it can be kept very clean and means to heat the cell or to prevent radiation of heat therefrom can easily be applied.

6. In the case of forming a chlorate by electrolysis from a chlorid, as the chlorid decomposes conductivity thereof changes, and there is necessity of adjusting from time to time the temperature of the electrolyte and the density of electrical current. Now, according to my invention, as the apparatus consists of a number of cells of a cylindrical form the terminals of electrodes of these cells being connected by conductors in parallel system, the temperature of electrolyte and the density of electrical current of any of the cells can be easily maintained in any desired degree. Moreover, as the electrolyte flows from one cell to another with a constant and uniform speed, the electrolyte can be electrolyzed under a most suitable condition. Thus with a small labor of adjusting the temperature of electrolyte and the density of electrical current, a greatest electrolytical efficiency can be secured.

7. The reservoir of electrolyte, electrolyzing cells and crystallizers are connected with one another in such a way that from the time when the electrolyte leaves the reservoir until it comes out of the last crystallizer as mother liquor, excepting the easy work of testing the electrolyte and the shifting of the last outlet pipe from one series of crystallizers to another, everything is done automatically, which saves much labor and minimizes the loss of the electrolyte. Thus my invention has great economical advantage.

I wish it understood that any other form of construction can be used so long as it does not depart from the spirit of my invention.

Having now particularly described and ascertained the nature of my said invention,

I claim:—

1. An apparatus for manufacturing chlorates by electrolysis comprising a cell, an electrode arranged on the inner surface of the cell, a second electrode within the cell and uniformly spaced from the first electrode, and means for causing the electrolyte to flow upward and between the confronting surfaces of the electrodes.

2. An apparatus for manufacturing chlorates by electrolysis, consisting of a cell having one electrode arranged on the inner surface of the tubular or cylindrical body of the said cell; the other electrode in the form of a cylinder, solid or hollow, placed within the said body of the cell concentric therewith; and in which the electrolyte is made to flow upward in divergent directions uniformly and constantly, and to overflow from an upper part of the cell body, substantially as and for the purposes hereinbefore set forth.

3. An apparatus for manufacturing chlorates by electrolysis, consisting of a cell having an anode composed of a number of platinum wires arranged on the inner surface of the tubular or cylindrical body of

the cell; the cathode in the form of a cylinder, solid or hollow, placed within the body of the cell concentric therewith; and in which the electrolyte is made to flow upward from below the electrodes, substantially as and for the purposes hereinbefore set forth.

4. An apparatus for manufacturing chlorates by electrolysis, consisting of a cell having one electrode arranged on the inner surface of the tubular or cylindrical body of the cell; the other electrode in the form of a cylinder, either solid or hollow, placed within the body of the cell concentric therewith; and in which the electrolyte is made to flow upward from below the electrode the cell being so constructed that excepting the passage for the electrolyte and the openings for the gas evolved therefrom to escape, the whole is tightly closed, and the electrodes are placed in such positions that their junctions with their terminals never come into contact with the electrolyte and the gas, substantially as and for the purposes hereinbefore set forth.

5. An apparatus for manufacturing chlorates by electrolysis, consisting of a cell having one electrode arranged on the inner surface of the tubular or cylindrical body, separable into several pieces, of the cell; the other electrode in the form of a cylinder, either solid or hollow, placed within the body of the cell concentric therewith; and in which the electrolyte is made to flow upward from below the electrodes, substantially as and for the purposes hereinbefore set forth.

6. An apparatus for manufacturing chlorates by electrolysis, consisting of a cell having one electrode arranged on the inner surface of the tubular or cylindrical body of the cell; the other electrode in the form of a cylinder, solid or hollow, placed within the body of the cell concentric therewith; and a bottom in the shape of an inverted cone to receive a cathode supporter of corresponding shape, the cone surface of which cathode supporter being grooved with a number of grooves radiating from the apex of the cone in order to distribute uniformly the electrolyte introduced from below, substantially as and for the purposes hereinbefore set forth.

7. An apparatus for manufacturing chlorates by electrolysis, consisting of a cell having the anode arranged on the inner surface of the tubular or cylindrical body of the cell; the cathode in the form of a cylinder, solid or hollow, placed within the said body of the cell concentric therewith and firmly held from above by a head part, of glass, porcelain or the like, of the cell; and in

which the electrolyte is made to flow upward from below, substantially as and for the purposes hereinbefore set forth.

8. An apparatus for manufacturing chlorates by electrolysis, consisting of a number of cells, each of which having one electrode arranged on the inner surface of the tubular or cylindrical body of the cell; and the other electrode in the form of a cylinder, solid or hollow, placed within the said body of the cell concentric therewith; and in which the electrolyte is made to flow upward from below the electrodes in each cell, the whole being so connected that the electrolyte overflowing from an upper part of a cell is introduced into the next cell from below, substantially as and for the purposes hereinbefore set forth.

9. An apparatus for manufacturing chlorates by electrolysis, consisting of a number of cells; each of which having one electrode arranged on the inner surface of the tubular or cylindrical body of the cell; and the other electrode in the form of a cylinder, solid or hollow, placed within the said body of the cell concentric therewith; and in which the electrolyte is made to flow upward from below the electrodes in each cell, the whole being so connected that the electrolyte overflowing from an upper part of a cell is introduced into the next cell from below, and the terminals of the electrodes are connected by conductor in the parallel system, substantially as and for the purposes hereinbefore set forth.

10. An apparatus for manufacturing chlorates by electrolysis, consisting of a number of cells, each of which having one electrode arranged on the inner surface of the tubular or cylindrical body of the cell; the other electrode in the form of a cylinder, solid or hollow, placed within the said body of the cell concentric therewith; and in which the electrolyte is made to flow upward from below the electrodes in each cell, the whole being so connected that the electrolyte overflowing from an upper part of a cell is introduced into the next cell from below; the terminals of the electrodes are connected by conductor in the parallel system; and the whole can be connected successively with one and then another of several series of crystallizer, substantially as and for the purposes hereinbefore set forth.
